[57] CLAIM

The ornamental design for a surface pattern applied to a tire sidewall, as shown and described.

DESCRIPTION

FIG. 1 is an elevational view of the surface pattern applied to a tire sidewall; and,

FIG. 2 is an elevational view of an alternate embodiment of the surface pattern applied to a tire sidewall in FIG. 1;

The broken line showing of a tire sidewall in the drawing is for illustrative purposes only and forms no part of the claimed design.
